LIQUID DISPENSER

Max F. Gregor, Canoga Park, Calif.

Application August 29, 1932. Serial No. 630,919

3 Claims. (Cl. 221—102)

The invention relates to a liquid dispenser and more especially to an automatic holy water container and dispenser faucet.

The primary object of the invention is the provision of a device of this character wherein liquid, such as holy water, may be dispensed in a determined quantity, namely, in single drops, and the dispensing being automatically controlled without liability of waste or excess discharge of the contents of the container.

Another object of the invention is the provision of a device of this character, wherein the same is of a construction that it may be conveniently supported upon a pedestal or other rest and is especially adaptable for religious institutions, particularly for installation in a church although the same may be usable in a private home as an article of devotion in connection with an age old religious practice in the use of holy water for public and private devotion, the device being of novel form and is operable to permit a single drop to be dispensed and deposited upon the hand or finger of the operator for the carrying out of sacramental rites.

A further object of the invention is the provision of a device of this character wherein the liquid is protected as the same is confined in a manner to prevent a user from placing his or her hands in the quantity of liquid and thus eliminating pollution and also preventing waste thereof, the device being thoroughly sanitary without liability of contagion in the continued use thereof.

A further object of the invention is the provision of a device of this character which is simple in construction, thoroughly reliable and efficient in its purpose, readily and easily operated, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is a vertical sectional view through a device constructed in accordance with the invention, the parts thereof being in normal position and the faucet closed.

Figure 2 is a sectional view on the line 2—2 of Figure 1 looking in the direction of the arrows.

Figure 3 is a perspective view of the operat-

ing lever or bracket for the faucet of the device.

Figure 4 is a top plan view of the cut-off plunger of the faucet.

Figure 5 is a side elevation of the valve.

Figure 6 is a sectional view on the line 6—6 of Figure 1 looking in the direction of the arrows.

Figure 7 is a sectional view on the line 7—7 of Figure 5.

Figure 8 is an elevation of the operating lever for the faucet.

Similar reference characters indicate corresponding parts throughout the several views in the drawing.

Referring to the drawing in detail, the device constituting the present invention comprises a container 10 preferably in the form of a glass jar, although it may be otherwise constructed and in this instance is provided with a contracted neck 11, the same being externally threaded for the detachable connection of a lid or cover 12 thereon. The container 10 is adapted to carry holy water 13 and the same is filled when its closed bottom end 14 is lowermost and the open contracted neck 11 uppermost with the cover or lid 12 removed, thus such water being introduced through the open neck 11 as will be obvious.

Centrally fitted in the lid or cover 12 is a tubular throat 15 having the threaded portion 16 which is passed through the lid or cover and has engaged therewith a coupling nut 17 so that in this manner the throat 15 will be detachably joined with the lid or cover, the latter resting against an external annular flange 18 on said throat 15 and thus a fluid-tight joint between said throat and lid or cover is had.

The throat 15 at its outer end is provided with a delivery opening 19 walled by a valve seat 20 with which is adapted to contact a ball closure or valve 21, the same being urged to contact with the seat through a coiled expansion spring 22, the latter resting against the perforated overhang 23 of the nut 17 and playing against the closure valve 21. The purpose of this valve or closure 21 is to seal the delivery opening 19 or close the same when the container 10 is inverted and being mounted for the discharge of its contents 13.

For association with the container 10 is a hollow cylindrical body forming a basin 24, the same fitted with a removable top 25 secured by fasteners 26, this top carrying a nipple 27 into which is telescopically fitted the throat 15, the basin 24 being in communication with the container 10 by the throat 15 through its delivery opening 19, the basin being formed interiorly in alignment

with the longitudinal axis of the throat 15 with the lug 28 rising from the bottom of said basin and this lug carries a lift pin 29 which projects the required distance to engage with the closure 5 or valve 21 for lifting the same from the seat 20 and thereby uncovering the opening 19 so that the water 13 within the container 10 can flow therefrom through the throat 15, opening 19 in the basin 24 as will be clearly apparent from Figure 1 of the drawing.

Secured at the periphery of the basin 24 exteriorly thereof is a fixture including the bracket 30, the nipple 31 and the discharge faucet 32, the latter being in the form of a barrel vertically 15 disposed and at right angles to the nipple 31 which has communication with the basin 24 through the port 33 in its side wall and registering with the said nipple.

Arranged within the barrel 32 is a slidable tubular plunger 34, the barrel 32 at its lowermost end being formed with a discharge opening 35 with which engages a valve 36, the stem 37 of which fits within the plunger 34 and this stem being provided with opposed longitudinally directed vent channels 38 opening through the upper end of the plunger 34. The valve stem 37 has a reduced upper end portion 39 slidably through a guide 40 fixed to the bracket 30 by fasteners 41. The reduced upper portion 39 of the stem 37 is surrounded by a coiled tensioning spring 42 the same resting upon the guide 40 at its lower end while its upper end plays against a washer 43 held against a cross pin 44 mounted in said reduced portion 39 of the stem at its upper end. 35 This spring 42 functions to hold the valve 36 against the seat 35 for the closing of the faucet of the device. The stem 37 spaced inwardly from the valve 36 is formed with an abutment 45 to be engaged by the plunger 34. This engagement 40 takes place in advance of the opening of the valve 36 so that the plunger 34 will have moved in the barrel 32 for cutting off communication thereof with the basin 24 through the nipple 31. Prior to the opening of the valve 36 said plunger 45 upon engaging the abutment 45 will force the valve to open position and in this action the water will be dispensed in drops, that is to say, a single drop to each opening movement of the valve 36.

50 Carried by the bracket 30 is a hand operated lever 46 which is preferably bifurcated at 47 for straddling the nipple 31 and which lever is swingingly supported by a pivot 48 engaged in the bracket 30. At the upper end of the plunger 34 are opposed laterally extending lugs 49, these loosely engaged in forked terminals 50 of bell crank-like arm extensions 51 of the lever 46, the free end of the lever being formed with a finger engaging button or head 52. It will be seen that when pressure is applied to the lever the plunger 34 will be shifted downwardly upon the valve stem 37 and in this movement communication between the barrel 32 and the basin 24 is shut off the instant that contact of the plunger is had with the abutment 45, whereupon the stem 37 is moved downwardly and the valve 36 freed from its seat 35 and a single drop of water is dispensed through the discharge opening in the lower end of the barrel 32 of the faucet. This drop of water will become deposited on the finger of the operator of the lever 47. The pivot 48 for the lever 46 supports a leaf spring 53 which operates against the lever 47 to move the same outwardly whereby the arm extensions 51 will swing upwardly and the

forked terminals 50 engaged with the lugs 49 will cause the lifting of the plunger 34 in the barrel 32. Simultaneously with this upward movement of the plunger 34 the valve 36 will move to closed position under the action of the spring 42 upon the reduced end 39 and thus the said valve will close the opening in the lower end of the barrel 32, thereby shutting off the dispensing of the water.

The lower discharge end of the barrel 32 is shaped to form a single drop trapping space 54 for the water admitted thereto from the nozzle 31 through port 33 of the basin 24.

The throat 15 has formed at its outer open end concentrically of the opening 19 therein a reduced circular nozzle 55 which projects into the basin 24 and the same determines the water level within said basin as should be apparent in Figure 1 of the drawing.

In the working of the device, it being preferable to have the same supported upon a pedestal or other place of rest (not shown), the bottom of the basin 24 being formed with securing ears 56, an operator through the instrumentality of his or her finger presses upon the head 52 of the lever 46 moving the same against the resistance of the spring 53 and this movement causes the lowering of the plunger 34 shutting off communication between the barrel 32 and the basin 24. When the plunger 34 engages the abutment 45 the further downward movement of said plunger will then cause the valve 36 to open and at this instant a single drop of the sacred water 13 is dispensed or discharged. By reason of the disposition of the head 52 of the lever the single discharged drop of water will become deposited on the finger of the operator of the device. Immediately upon the release of pressure upon the lever 46 the spring 53 becomes active for the lifting of the plunger 37 by the arms 51 and when the said plunger recedes from the abutment 45 the spring 42 on the end 39 of the plunger 34 will respond to bring the valve 36 to closing position with respect to the discharge opening 35 in the barrel 32, thereby shutting off the faucet. The instant that communication is established between the barrel 32 and the basin 24 the trap 54 will become filled with the determined quantity of water, 125 the size thereof permitting a single drop to be dispensed in the working of the device.

What is claimed is:

1. A device of the character described comprising a liquid container, a basin for communication with the container, a removable cap on the container, a delivery throat on the cap and removably fitted with the basin, means normally closing the throat, means in the basin and opening the closing means of the throat when the latter is engaged with said basin, and a faucet communicating with the basin and provided with means adapted to dispense single drops of liquid therefrom.

2. A device of the character described comprising a liquid container, a basin for communication with the container, a removable cap on the container, a delivery throat on the cap and removably fitted with the basin, means normally closing the throat, means in the basin and opening the closing means of the throat when the latter is engaged with said basin, a faucet communicating with the basin and provided with means adapted to dispense single drops of liquid therefrom.

liquid therefrom, and control means arranged with the faucet and manually operable.

3. A device of the character described comprising a liquid container, a basin for communication with the container, a removable cap on the container, a delivery throat on the cap and removably fitted with the basin, means normally closing the throat, means in the basin and opening the closing means of the throat when the latter is engaged with said basin, a faucet

communicating with the basin and provided with means adapted to dispense single drops of liquid therefrom, and control means arranged with the faucet and manually operable, said manually operable control means being disposed with respect to the faucet for the deposit of droppings onto a finger of the operator of said means.
